UNITED STATES PATENT OFFICE.

ARTHUR WILMOT HORSEY AND HENRY HOGUE VAUGHAN, OF MONTREAL, QUEBEC, CANADA,
ASSIGNORS TO AMERICAN LOCOMOTIVE COMPANY, A CORPORATION OF NEW YORK.

SUPERHEATER FOR STEAM-BOILERS.

No. 904,129.

Specification of Letters Patent.

Patented Nov. 17, 1908.

Application filed February 7, 1906. Serial No. 300,022.

To all whom it may concern:

Be it known that we, ARTHUR W. HORSEY, a subject of King Edward VII, and HENRY H. VAUGHAN, a citizen of the United States, both residents of Montreal, Canada, have invented a certain new, useful, and Improved Superheater for Steam-Boilers, of which the following is a full, clear, and exact description, such as will enable others skilled in the art to which it appertains to make and use the same.

Our invention relates to superheaters for steam boilers and has particular reference to improvements upon superheaters for locomotive boilers, that is, such as have a plurality of fire-tubes.

It is customary to use a portion of the heat from gases of combustion as they pass from the boiler to the stack for superheating the steam from the boiler. The saturated steam from the dry-pipe is conducted to the point of use, usually the engine steam chest or chests, through a passage-way of large superficial area, which is exposed to the hot gases from and in the flues of the boiler. This passage-way constitutes the superheater, the steam therein absorbing heat from the gases and taking on a higher temperature.

Heretofore in locomotive practice, it has been customary to arrange a header in the smoke box, said header being a single member, divided by suitable walls or partitions into two or more compartments. In superheaters of this class, the saturated steam from the boiler is delivered into one compartment of the header and flows thence through tubes arranged in the front end of the boiler and thence back into another compartment of the header. While a certain degree of superheat is obtainable with this construction, such a superheater is not as economical or efficient as might be for the reason that the superheated steam upon returning to the header loses considerable of its heat through contact with the walls which confine the saturated steam. The saturated steam being of lower temperature than the superheated steam keeps the common walls or partitions much lower in temperature than said superheated steam and therefore constantly extracts heat from said superheated steam, thereby lowering its temperature. Such headers, as now used, are generally made in sections, bolted together. Again, the superheating tubes are arranged

behind the header or headers and are so connected to said header as to make it difficult to remove them unless one or more sections of said header are also removed. So constructed it is difficult to ascertain which of the several superheating tubes is at fault when a leak is discovered; and, furthermore, when detected the fault is difficult to remedy. It is also necessary to remove the tubes of these superheaters in order to clean or renew the same from time to time. Another disadvantage lies in the fact that the present superheaters are not properly supported in the front end and flues of the boiler and for this reason are a source of both annoyance and danger. This fault is particularly noticeable at the return bends of the superheating flues, which, being free to vibrate, rattle against the containing fire tubes. Furthermore, the return bends which are now used for connecting the rear ends of the superheating tubes occupy so great an area in the fire tubes and are of such form as to favor the accumulation of solid matter thereon, and cause the frequent clogging or stopping of the fire flues or tubes.

The primary object of our invention is to improve the construction and the arrangement of superheaters in and upon fire-tube boilers and to increase the efficiency thereof.

Particular or special objects of the invention are: to provide a superheater which shall constitute a substantially direct passage between the dry-pipe and the steam feed or discharge pipe which supplies the engine;— to provide a superheater which shall be of such form as to avoid the interchange of heat between the saturated and superheated steam through metallic contact, as is the case in the superheaters now in use;— to provide a superheater which shall offer the least possible obstruction to the passage of the steam; *i. e.*, one in which the steam passages shall be arranged to avoid the creation of conflicting or impinging streams or currents of steam;— to provide a superheater which shall be especially adapted for installation in the front ends of locomotive boilers;— to provide a superheater in which the parts or members shall be rigidly connected and held against vibration;— to provide a superheater which may be easily dismembered, and from which one or more of superheating tubes may be removed without disturbing the others and practically without interrupting the op-

- eration of the superheater;—to provide a superheater in which the greater number of parts shall be of uniform shape and size and consequently easy to repair or replace;—to 5 provide a superheater wherein the superheating tubes shall be connected with the headers in such manner that the connections shall be upon the front of the headers and easily accessible;—to provide a superheater 10 that shall have a plurality of superheating tubes arranged in the fire tubes of the boiler, but the construction of which shall, notwithstanding, be such as to permit the fire tubes to be readily cleaned;—to provide a 15 superheater of the type having a large number of superheating loops or tubes arranged in the boiler flues and to equip said loops with bends or turns of a form adapted to prevent the accumulation of solid matter 20 thereon, whereby the fire-tubes shall be kept clear.

A further and particular object of the invention is to provide means for protecting the superheater from the intense heat of the 25 hot gases when steam is cut off from the superheater; and further to provide means of this kind which shall automatically operate in response to the throttle to cut off or permit and indicate the flow of gases 30 through the boiler tubes which contain parts of the superheater, according as steam is cut off from or admitted to the superheater.

Still further objects of our invention will appear hereinafter.

35 Our invention consists generally in a steam superheater which comprises two distinct headers, for connection respectively with the boiler dry-pipe and the steam feed or supply pipe, in combination with a plurality of 40 superheating tubes having respective ends connected with said headers, said tubes being arranged in the path of the hot gases between the boiler and the stack and, generally, within the fire-tubes of the boiler.

45 Our invention also consists in a superheater broadly characterized as above in which the headers are of comb-like structure, to present a plurality of parallel sub-headers, to which sub-headers the ends of the superheating tubes may be conveniently connected.

50 Our invention also consists in the combination of a boiler and its front end with a superheater comprising a plurality of superheating tubes and headers whereto the tubes 55 are connected, the whole being characterized by the arrangement of one of the headers at the top of the smoke box for ready connection with the boiler dry-pipe, and by the arrangement of the other header at a lower 60 point.

Our invention also consists in various details of construction and combination of parts;—all as hereinafter described and particularly pointed out in the claims.

65 Our invention will be more readily under-

stood by reference to the accompanying drawings which form a part of the specification, and in which

Figure 1 is a longitudinal vertical section of the front end of a locomotive boiler, illustrating a superheater embodying our invention; Fig. 2 is a section on the line 2×—× of Fig. 1; Fig. 3 is an enlarged section through one of the enlarged flues or fire-tubes showing the superheating tubes therein, viewed 70 in the direction of the fire-box; Figs. 4 and 5 are detail views of one of the return bends used on each superheater tube, Fig. 4 being a horizontal section and Fig. 5 is a side elevation thereof; Fig. 6 is an enlarged detail 75 illustrating the manner in which the forward ends of the superheating tubes are attached to the headers; Fig. 7 is a front elevation of the headers, slightly modified in design.

80 We have here shown our invention in the form in which we prefer to construct or embody it, and in which form it is efficient, durable and most satisfactory to engineers.

The superheater herein shown is one of the 85 several containing the gist of our invention all of which may be constructed within the scope of the invention, this particular superheater differing from the others in special features, details and characteristics which fit 90 it for use in and upon locomotive boilers.

95 As shown in the drawings, A represents a locomotive boiler, having a large number of fire tubes C extending between its flue sheets L. The upper part of the boiler contains a 100 number of larger fire-tubes C' to contain the steam pipes or tubes, of the superheater. These occupy considerable space in the enlarged fire-tubes, and to make the free cross sectional area of the fire-tubes the same 105 throughout, the rear ends of the tubes C' are reduced in diameter at their rear ends near the fire-box flue sheet, as shown at points 16'.

110 B represents the steam dome of the boiler and E is the dry-steam pipe containing the throttle valve D and leading from the dome to an expansion joint or coupling provided in the front flue sheet L of the boiler. The boiler has the usual front end or smoke-box 115 F having the stack H and an exhaust nozzle G, above which latter are the petticoat pipes K.

120 The saddle, the cylinders and steam chest are represented below the smokebox, and M—M represent the steam feed or supply pipes which connect with the live steam passages in the saddle, and therethrough to the steam chests.

An apron or baffle-plate 23 having a top 125 section 24 extends from the upper part of the flue sheet and downward to the top of the exhaust nozzle G, terminating in a supplementary apron 23' in front of said nozzle. The usual cinder or spark screen is repre- 130

sented in the smokebox. The gases passing from the firebox through the flues are forced to descend to the lower part of the smokebox and pass through the screen before reaching 5 the stack, the smoke-box being divided into two compartments by said apron.

For a purpose hereinafter explained, we 10 arrange to divide or close off the upper part of the compartment O back of the deflector or apron in order to shut off the flow of gases through the upper tubes of the boiler, and in this upper part O we arrange our superheater.

Briefly described, our superheater comprises the saturated steam header 1, the body 15 of which is located above the enlarged fire tubes, C', of the boiler, the superheated steam header 3, the body of which is located below the fire tubes, C', and a large number of 20 small steam pipes 10. Each pipe 10 is in the form of a loop that extends back into one of the enlarged fire-tubes of the boiler. In each case the forward ends of the steam pipe or loop 10 are connected with the headers 1 25 and 3 respectively. The steam which enters header 1 is distributed in the pipes 10, and after being subjected to the heat within the fire-tubes returns to and is collected in the lower header 3, whence it is conveyed to the 30 engine steam chests.

The header 1 is provided with a rearwardly extending pipe-section or neck 1' located centrally as shown in Fig. 2, and connected with the dry pipe E of the boiler. 35 The ends of the header 3 are provided with forwardly extending bosses and flanges, and have openings which communicate with the steam feed pipes M—M of the two engines, the upper flanges of said pipes being bolted 40 to the header 3 as shown in Figs. 1 and 2. Both headers are provided with wide bracket lugs extending approximately to the sides of the smoke-box and resting upon brackets 5 and 6 on said sides. The headers may be 45 rigidly bolted to these brackets, but ordinarily their weight is sufficiently great to render such fastenings unnecessary, provided the several lugs and brackets are formed to interlock and thus prevent horizontal lateral 50 movement of the headers. In addition to these fastenings for the header, it will be noted that they are made perfectly rigid by connection with the boiler flue sheet and the feed pipes M.

55 Furthermore, as will appear from inspection of the drawings, we prefer to place the supporting lugs above the respective centers of gravity of the headers so that the headers will swing from the brackets 5 and 6, and 60 maintain their positions when first loosely placed in the front end of the boiler.

A first and most important object,—to-wit, the complete separation of the saturated and superheated steam containers,—is attained in 65 the structure thus far described, the headers

being separate bodies and free from contact throughout. The saturated or low temperature steam which enters the upper header can in no wise affect or lower the temperature of the superheated steam in the other header. 70 The headers are distinct structures, and the only heat communication between them is through the superheating tubes.

It is desirable that the superheating tubes shall be of standard or uniform dimensions. 75 We secure this advantage and at the same time adhere to the idea of forming the headers as separate bodies by providing the horizontal body of each header with a plurality of perpendicular header branches 2 and 4 80 respectively. The header bodies are made to correspond with the design of the boiler and the layout of its fire tubes and the header branches occupy alternate positions between the vertical rows of boiler fire-tubes. In 85 these positions it is an easy matter to connect the ends of the superheating tubes to the header branches. The formation of the downwardly extending header branches on the upper header body, and the upwardly 90 extending header branches or fingers on the lower header body gives the headers the appearance of two intermeshed combs, and the relatively wide spaces between the alternating header branches permit the superheating 95 tubes to be freely inserted or withdrawn from the thus exposed boiler fire-tubes, after the headers have been secured in their places.

The ends of the header branches and the adjacent surfaces of the header bodies are 100 provided with interlocking points or lugs, serving to hold the headers in place while the tubes are being applied. The metallic contact between the lugs, and hence between the two headers, is of such slight extent that 105 it is negligible as a factor in heat conduction; otherwise any such connection would be objectionable, for reasons before pointed out. Each header body, with its communicating header branches is preferably a single 110 metal casting. The headers may be readily manufactured in the forms shown and by so doing we avoid the packed joints that have proved so objectionable in other superheaters. In casting the headers, it is an easy matter 115 to form the fronts and backs of the header-branches on converging lines, as shown in Fig. 1, and this is done in order that the cross sectional area thereof shall correspond to the areas of the pipe connections which 120 enter at different elevations.

We prefer that the superheating tubes shall be attached to the headers at points where the connections or joints will be accessible; that is, to the forward faces of the 125 headers, where the parts may be readily got at when the deflector plate 23 is removed. We therefore provide the fronts of the header branches with a number of holes to receive the ends of the pipes 10. Because 130

of the great number of these pipes and because it would be undesirable to make so many holes in the header branches, we reduce the necessary number of openings by 5 employing union connections 9 on the header branches. These connections, as shown in Fig. 2, are single, double or quadruple, according to position. A detail view of a quadruple union or connection is given in 10 Fig. 6, from which it will be seen that the union 9 is provided with a neck or boss that is screwed into the hole in the header branch. The connection bosses are at right angles to the neck, and the elbow formation is 15 preserved in the forward end of the casting, presenting itself in an inwardly projecting portion 9' wherein the several curves are merged.

The ends of the superheating loops 10 are 20 provided with flanges 10' and are brought forward to the connections 9, whereto they are joined by union couplings 14. The pipes 10, the flanges 10', the unions 14 and the necks of the members 9 are of uniform size 25 throughout and hence are interchangeable. The union connections 9 may also be of uniform size, but to avoid leaving a number of openings to be plugged, and to maintain a uniform flow of steam through the pipes 30 connected with the single, double and quadruple unions, we prefer to make them of different sizes and to proportion their internal dimensions to the number of superheating pipes connected to each. These different sizes are represented in the header 35 openings at the right hand of Fig. 2.

We have hitherto spoken of the superheating pipes as though each were formed of a single bent pipe or tube, but it will be 40 understood that such form would be expensive and otherwise objectionable, and that each loop is made up of two pipe sections 10 having their rear ends joined by an elbow 17. The pipes are carried back in 45 the fire-tubes C', and the elbows are located near the shouldered or reduced ends of said tubes. We prefer to place two loops in each fire-tube, and, as shown, their elbow castings lie one upon the other. These elbows 50 or return bends 17 are of a novel form sufficiently important to require detailed description. Considered strictly as elbows or return bends, they perform the ordinary function of connecting the pipes; but they 55 are distinguished from other elbows by the pointing of their ends and other projections.

We have found that the return bends usually employed in superheaters which present flat or approximately flat surfaces to 60 the gases moving through the fire-tubes cause or favor the accumulation of solids upon and against the elbows, not infrequently resulting in the clogging of the fire-tubes. To avoid this difficulty, we provide each elbow 65 with a sharp end or point 18 presented

toward the fire-box which is kept clean by the attrition of the gases and moving solids.

The elbows 17 are provided with interlocking or engaging lugs 19 which serve to hold them apart, and the elbows are also 70 provided with lugs 20 that serve to center the group of pipes in the fire-tubes. It should be noted that the lugs 19 and 20 of the return bends 17 are pointed like the bend or elbow itself and for the same purpose. 75

The particular advantages of the construction described are that contact between the superheating and fire-tubes is prevented, and the superheating tubes are held against objectionable vibration. The superheating 80 tubes are rigidly held and are properly spaced at their forward ends and also at their rear ends, the fire-tubes are easily accessible between the headers of the superheater, both the fire-tubes and the superheating pipes may be effectively and easily cleaned without dismembering or removing any parts of the superheater. The superheating tubes, by reason of their construction and positions, may be quickly removed 90 when need be, as for purposes of repair or renewal.

If it becomes necessary to remove one or more tubes when no others are at hand to replace them, the pipes are simply taken out 95 and the union couplings plugged, after which the superheater is ready for further use.

In referring to the adaptability of our superheater to repair and continued use while on the road, we desire also to call attention to an advantage attaching to the use of the separate short steam feed pipe M. If one engine of the locomotive breaks down, it may be quickly disconnected from the superheater and boiler by simply removing the 105 pipe M and closing the opening in the superheater by means of a plate which will be provided for such emergencies, after which the superheater will continue to supply steam to the opposite engine. 110

A principal objection to the use of superheaters, particularly upon locomotives, has been based upon their lack of durability. It has been found that the small superheating pipes burn out quickly and are much shorter 115 lived than the other parts of the boiler. We find that this is due to the fact that the superheating pipes are subject to the high temperature throughout the time that the boiler is under fire. Now it is plain that when the throttle is open, the superheater, being filled with steam, is protected thereby, but when the steam is cut off, the pipes, being no longer cooled by the steam, are burned by the hot furnace gases. As a consequence, the 125 pipes quickly give out and cannot be relied upon for any extended period. We obviate this difficulty by providing means for shutting off the flow of hot gases upon the superheater when it is deprived of steam, said 130

means comprise a damper 22 arranged below the forward end of the superheater; that is, between the flue-sheet and the superheater at a point below the lowest tier of superheating tubes. When this damper is closed, the upper compartment O of the smokebox is closed off from the remainder of the smokebox, and, obviously, the flow of hot gases through the upper tubes of the boiler 10 is interrupted. In this manner the temperature within the enlarged fire tubes is much diminished, and the superheating pipes are saved from a temperature that would be destructive. The lower header of the superheater, with its horizontal flange 25, forms a partial floor for the compartment O, and the damper 22 is arranged to close against the rear side of said header 3, thus completely shutting off the exit of gases at that point. The damper 22 may be adapted for operation from the engine cab; that is, it may be operated from the throttle valve lever or by an independent lever; but we prefer to employ an automatic damper operating mechanism which shall respond directly to the action of the throttle valve without imposing any extra load upon the throttle lever. This mechanism comprises a small steam cylinder 30 and its piston, which 30 latter has its rod connected with an arm 31 that is fixed on the end of the damper shaft 27 outside the smokebox.

The steam end of the cylinder 30, is supplied with steam through a pipe 30' leading 35 from one of the steam chests or connected in any other suitable manner with the locomotive dry pipe. When the throttle valve is open, the steam admitted to the cylinder 30 will force out the piston and hold the 40 damper 22 open, while when the pressure is relieved the piston will retire and permit the damper to be closed by a suitable spring, or by a weight 32 arranged on an arm extending from the shaft 27. This mechanism will 45 operate properly as long as the shaft 27 and damper 22 remain intact; and the superheating pipes will be automatically exposed to and protected from the furnace heat according as the throttle is opened or closed. 50 It is obvious, however, that being in the direct line of the hot gases emerging from the boiler flues, the damper will ultimately burn out; and if this should occur during the run of a locomotive, the engineer should 55 be warned. To this end we arrange a target on the other, (the engineer's) side of the locomotive, the target comprising an arm 34,—preferably carrying a disk 35 and connected to the shaft 27. This has the normal 60 function of informing the engineer of the position of the damper, the target being raised when the damper is opened and lowered when the damper is closed. (See dotted lines Fig. 1.) If the shaft 27 is burned 65 away, it is obvious that the target will be

disconnected from the damper operating mechanism, and, falling, will assume an abnormal position and thereby attract the attention of the engineer.

We have herein described the specific 70 structure which we consider to be best adapted for locomotives, but it will be understood that our invention is not confined or limited to this structure, which may be modified by any skilled person without departing from 75 the spirit of our invention.

Having thus described our invention, we claim as new, and desire to secure by Letters Patent:

1. A superheater comprising a saturated 80 steam header body located above a set of superheating fire tubes and having a plurality of header branches extending downwardly between the vertical rows of said fire tubes, a superheated steam header located below the set of superheating fire tubes and having a plurality of header branches extending upwardly and alternated in position with the saturated header branches, and a plurality of loops of superheating pipe connected at their ends to the saturated and 85 superheated header branches respectively. 90

2. A superheater comprising a saturated and a superheated steam header body, each having a plurality of header branches, the 95 saturated and superheated steam header branches being relatively alternated in position, and a plurality of loops of superheating pipes connecting a header branch to the two adjacent header branches. 100

3. In a steam boiler superheater, the combination of a plurality of vertical rows of loops of superheating pipe, a saturated and a superheated steam header body, each having a plurality of header branches which are 105 alternated in position on the two header bodies and extend vertically between the rows of superheating pipe loops, and connections between the superheating pipe loops on either side of the header branches, alternately with 110 a saturated and a superheated header branch.

4. A superheater for locomotive boilers comprising two parallel header bodies provided with a plurality of relatively perpendicular parallel header branches spaced to 115 correspond with the flues of a boiler, and a plurality of superheating pipes extending from the forward side of said header branches and backwardly between respective header branches, substantially as described. 120

5. A superheater comprising a plurality of alternated saturated and superheated steam header branches, in combination with a plurality of superheating pipes arranged behind said header branches and having flanged 125 ends and unions whereby they are connected to the fronts of said header branches, substantially as described.

6. A superheater comprising a plurality of parallel alternated saturated and superheat- 130

- ed steam headers, each provided with a plurality of plural union couplings, said couplings being disposed upon the outer sides of said headers and rearwardly extending 5 perheating loops suitably joined to the said unions, substantially as described.
7. A fire tube boiler having the usual fire flues and smoke box, in combination with a superheater in said smoke box and flues, said 10 superheater comprising a saturated and a superheated steam header body, each having a plurality of header branches disposed in relatively alternated position on the header bodies and between vertical rows of flues, so 15 as to afford access to the flues, and a plurality of superheating tubes extending in said flues and having their ends connected to said header branches.
8. In a superheater for fire tube boilers, 20 a plurality of alternately disposed steam header branches, which are spaced apart to afford access to the flues of the boiler, and a plurality of superheating pipes extending in said flues and having their ends connected to 25 said header branches.
9. A superheater comprising a plurality of parallel saturated and superheated steam header branches in combination with a plurality of superheating loops comprising 30 pipes, extending between said header branches and joined to the front walls of said header branches.
10. A steam boiler, in combination with a plurality of parallel saturated and superheated steam header branches spaced between 35 and to correspond with the flues of a boiler, and a plurality of superheating pipes each connected with two of said header branches, substantially as described.
- 40 11. A locomotive boiler containing a plurality of vertical rows of flues, in combination with superheating loops or pipes extending in said flues, and a plurality of saturated and superheated steam header branches connected with said superheating loops, there being one of said saturated steam header branches for each two vertical rows of flues, substantially as described.
12. A locomotive boiler containing a plurality of vertical rows of flues, in combination 50 with superheating loops or pipes, extending in said flues, and a plurality of saturated and superheated steam header branches connected with said superheating loops, there being one of said superheated steam header branches for each two vertical rows of flues, substantially as described.
13. A locomotive boiler containing a plurality of vertical rows of flues, in combination 60 with superheating loops or pipes arranged in said flues, and a plurality of saturated and superheated steam header branches connected with said superheating loops, there being one saturated and one 65 superheated steam header branch for each

two rows of flues and said saturated and superheated steam header branches being respectively alternated and spaced to correspond with the spaces between said rows of flues, substantially as described.

70

14. A locomotive boiler containing two flues, in combination with a superheating loop or pipe in each flue, a steam header branch to which one end of each of said pipes is connected, and other header 75 branches, located on opposite sides of said first specified header branch, to which the opposite ends of said pipes are connected, substantially as described.

15. In a superheater for fire tube boilers, a 80 plurality of alternated saturated and superheated steam ducts or headers, respectively, joined at their upper and lower ends and a plurality of superheating loops or pipes extending in fire tubes of a boiler and having 85 their ends connected with said headers; whereby steam entering the saturated steam passage is divided into minute streams of substantially equal length between the point of admission and the point of discharge, sub- 90 stantially as described.

16. In a superheater for fire tube boilers, a plurality of superheating loops extending in vertical rows of fire tubes, in combination with saturated and superheated steam header 95 branches or passages, located in planes between the axes of the rows of fire tubes, and supplying steam to and receiving steam from the loops or pipes on their opposite sides, substantially as described.

100

17. In a steam boiler superheater, the combination of header branches located between vertical rows of fire tubes, and superheating loops or pipes extending in the fire tubes and connected to the header branches, substan- 105 tially as described.

18. In a steam boiler superheater, the combination of alternated saturated and superheated steam header branches, and superheating pipes or loops in rows of boiler 110 tubes, the superheating pipes in the rows of boiler tubes on opposite sides of a header branch being connected thereto, substantially as herein described.

19. A superheater comprising a saturated 115 steam header body, in combination with a superheated steam header body, a plurality of header branches depending from the saturated steam header body, a plurality of header branches extending upward from the 120 superheated steam header body, between the header branches of the saturated steam header body, and suitable superheating pipes or loops extending in fire tubes of a boiler and connected, at their opposite ends, to said saturated and superheated header branches, respectively, substantially as described.

20. A fire tube boiler having the usual smoke box, in combination with two separate groups of steam header branches disposed in 130

said smoke box, parallel with the front flue sheet, one thereof being connected with the dry pipe of the boiler and the other with the steam engine or engines, and a plurality of 5 looped superheating tubes having their ends connected with said groups of steam header branches, and extending between the header branches of said groups and in the fire tubes of said boiler, substantially as described.

21. A superheater comprising saturated and superheated steam header branches, located forward of the front flue sheet of a locomotive boiler, in combination with a plurality of superheating loops or pipes connected to the forward sides of said header branches and passing rearwardly between them, substantially as described.

22. A boiler and its front end, in combination with a saturated steam header body sup-

ported in the upper part of said front end 20 and connected with the boiler dry pipe, a superheated steam header body supported in the lower part of said front end, a plurality of superheating pipes extending in loops or pairs in flues of the boiler and connecting 25 said header bodies, and a steam feed pipe connected to the lower header body, substantially as described.

In testimony whereof, we have hereunto set our hands, this 10th day of January, 30 1906, in the presence of two subscribing witnesses.

ARTHUR WILMOT HORSEY.
